UNITED STATES PATENT OFFICE.

EUGEN A. BOFINGER, OF NEW YORK, N. Y.

TYPE-WRITER CIPHOGRAPH.

SPECIFICATION forming part of Letters Patent No. 630,848, dated August 15, 1899.

Application filed August 11, 1898. Serial No. 688,379. (No model.)

To all whom it may concern:

Be it known that I, EUGEN A. BOFINGER, a citizen of the United States, residing at New York, borough of Manhattan, and State of New York, have invented certain new and useful Improvements in Type-Writer Ciphographs, of which the following is a specification.

This invention relates to a ciphograph for type-writers or other key-operated instruments, the same being in the nature of an attachment which can be placed over the keyboard of a type-writer machine or other key-operated instrument whereby messages may be written in cipher in the ordinary text by the operator of the machine, which message or communication can be retranslated into the original text on another type-writer or key-operated instrument in possession of the receiver.

The object of the present invention is to provide means for the adjustment of the keys or finger-pieces of the ciphograph so that they can be arranged to act upon the keys of a type-writer or other key-operated instrument no matter what be the disposition of the keys of the latter.

The invention consists of a ciphograph attachment for key-operated instruments which comprises a suitable rigid frame adapted to be supported above the keyboard of such key-operated instruments, laterally-shiftable auxiliary keys or finger-pieces movable to and from each other, and means for adjusting and setting said auxiliary keys or finger-pieces in position according to the diagram of the keyboard.

The invention also consists of certain other features of construction and combinations of parts to be hereinafter described and then claimed.

In the accompanying drawings, Figure 1 is a side elevation of my improved ciphograph attachment shown mounted on the keyboard of a type-writing machine. Fig. 2 is a vertical transverse section of the same. Fig. 3 is a sectional plan view of the ciphograph. Fig. 4 is a transverse section through the side rails of the machine, showing also one of the shiftable supporting-bars. Figs. 5, 6, and 7 are sectional and perspective details of the different parts of the shiftable supporting-

bars, showing how the guide-blocks for the shanks of the auxiliary keys or finger-pieces are adjusted. Figs. 8, 9, and 10 are plan and sectional views showing more clearly the construction of the guide-blocks for the auxiliary keys or finger-pieces.

Similar letters of reference indicate corresponding parts.

Referring to the drawings, A indicates the keyboard of a suitable type-writing machine, provided with ordinary keys a.

B indicates the main frame of the ciphograph attachment, which is applied over the keyboard of the type-writing machine and which is provided with depending legs b, which are longitudinally slotted at b' to receive set-screws b², whereby the said main frame is adjustably connected as to its vertical movement with the uprights or standards C, which are secured by bolts and nuts C' to the main frame of the type-writing or other machine, as shown. The main frame B is provided at its upper part at opposite sides with side rails D, which are provided with longitudinal slots d.

Referring more particularly to Figs. 2, 4, and 6, E indicates the transverse supports, one for each row of auxiliary keys or finger-pieces, each support E being composed of a back bar e, provided with end plates e', and a front bar e², which is hinged to the end plates at e³. From the end plates e' threaded studs e⁴ project, which pass through the longitudinal guide slots or ways d of the rails D and on which nuts e⁵ are screwed, so as to secure the key-supports E at any suitable point along said rails. The rails D are, as clearly shown in Fig. 4, channeled, so as to receive the end pieces or plates e'. Any suitable number of these transverse key-supports E are provided, according to the number of rows of keys or finger-pieces with which it is desired to equip the apparatus.

Referring more particularly to Figs. 8, 9, and 10, as well as to the figures just described, it will be seen that between the bars e e² are arranged a number of guide-blocks F, which are composed of sections F' F², the latter being provided with a projecting portion f, which fits tightly into a deeper recess f' in the other section F', so that the two sections F' F² are held together and whereby a suitable guide-

opening is formed, in which the flat shanks *g* of the auxiliary keys or finger-pieces *G* are guided.

The guide-block section *F'* is provided with 5 a spring-tongue *t*, which engages over the upper edge of the back bar *e* of the key-supports *E*, whereby the same is hung thereon, so as to permit the said section *F'* to be slid along said bar *e*. The shanks of the auxiliary keys or 10 finger-pieces are retained in the guide-openings in the guide-blocks *F* by means of the movable clamping-bar *e²*, which presses the movable section *F²* of the guide-blocks against the other section *F'*. The guide-blocks *F* are 15 locked into position and may be set or adjusted longitudinally of the key-supports by means of the spring-clamp *h*, which is bent up from wire and which is hinged at *h'* to the clamping-bar *e²*, so that its opposite bent end 20 *h²* can engage over the back bar *e* and enter a suitable recess *e⁶* in said bar *e*. The adjacent faces of the removable sections *F²* of the guide-blocks and the clamping-bar *e²* are 25 toothed or serrated, as shown, so that a fine adjustment may be obtained, and when the clamping-bar *e²* is locked into position by means of the clamp or fastening device *h* the guide-blocks are firmly locked so that they 30 cannot be shifted longitudinally along the key-supports.

The auxiliary keys or finger-pieces are adjusted according to the diagram of the keyboard of the type-writing or other key-operated machine by first adjusting the gangs or 35 rows of auxiliary keys or finger-pieces, which is accomplished by loosening the nuts *e⁵*, shifting the key-supports along to the desired position, and then again tightening up the nuts against the rails *D*. The individual adjustment 40 of the keys or finger-pieces relatively to their key-supports is accomplished by unlocking the clamping-bar *e²*, then resetting the guide-blocks for the shanks of the auxiliary keys or finger-pieces, and then locking 45 the clamping-bar *e²* in position, as shown in Fig. 5. If it is desired to transpose the auxiliary keys or finger-pieces as in my copending application, filed July 23, 1898, Serial No. 686,726, this can be accomplished by unlocking 50 the clamping-bars and removing the desired removable section of the guide-blocks, so that the shank of the auxiliary key or finger-piece can be pulled out, then inserting the shank of another key or finger-piece, and 55 readjusting and locking the blocks.

Besides the above adjustments, which are adapted to all diagrams of keyboards of key-operated instruments, provision is made for the vertical adjustment of the auxiliary finger-pieces according to the height of the keys 60 of the machine.

It is evident that various changes in the construction of the parts of the attachment for accomplishing the various adjustments 65 could be resorted to by skilled mechanics without departing from the scope and spirit of the invention.

Having thus described my invention, I claim as new and desire to secure by Letters Patent—

1. In a ciphograph, the combination, with a suitable rigid frame adapted to be supported above the keyboard of key-operated instruments, of laterally-shiftable auxiliary keys or finger-pieces movable to or from each other, 75 and means for adjusting and setting said auxiliary keys or finger-pieces in position according to the diagram of the keyboard, substantially as set forth.

2. In a ciphograph, the combination, with 80 a suitable rigid frame adapted to be supported above the keyboard of key-operated instruments, of auxiliary keys or finger-pieces movable to or from each other, means for laterally adjusting said keys or finger-pieces relatively to the diagram of the keyboard, and 85 means for vertically adjusting the auxiliary keys or finger-pieces according to the height of the keys on the keyboard, substantially as set forth.

3. In a ciphograph, the combination, with a suitable rigid frame, adapted to be supported above the keyboard of key-operated instruments, of auxiliary keys or finger-pieces adapted to act on the keys of the keyboard, and 95 means for vertically adjusting and setting said auxiliary keys or finger-pieces higher or lower according to the height of the keys of the instrument, substantially as set forth.

4. In a ciphograph, the combination, with 100 a suitable frame adapted to be supported above the keyboard of key-operated instruments, and guide-rails on said frame, of transverse key-supports arranged between the guide-rails, means for adjusting the key-supports along the guide-rails, and auxiliary keys or finger-pieces, supported by the key-supports, substantially as set forth.

5. In a ciphograph, the combination, with a suitable frame, adapted to be supported 110 above the keyboard of key-operated instruments, of a transverse key-support supported on said frame, auxiliary keys or finger-pieces, and means for adjusting the auxiliary keys or finger-pieces to or from each other and longitudinally of said key-support, substantially 115 as set forth.

6. In a ciphograph, the combination, with a suitable frame, adapted to be supported 120 above the keyboard of key-operated instruments, of a transverse key-support arranged on said frame, laterally-shiftable guide-blocks, means for adjusting the guide-blocks along said key-support, and auxiliary keys or finger-pieces, the shanks of which are guided in said 125 guide-blocks, substantially as set forth.

In testimony that I claim the foregoing as my invention I have signed my name in presence of two subscribing witnesses.

EUGEN A. BOFINGER.
